UNITED STATES PATENT OFFICE.

MORRIS BLOOMFIELD, OF NEW YORK, N. Y., ASSIGNOR TO TONELL-ROBITSCHEK CO., INC., OF NEW YORK, N. Y., A CORPORATION OF NEW YORK.

CAP.

Application filed October 21, 1925. Serial No. 63,821.

My present invention relates generally to articles of headwear, and has particular reference to caps of the type which embodies adjustable earlap portions, and to a method 5 of making the same.

It is an object of the invention to provide a cap having an earlap portion capable of being folded back over a crown or head portion when not in use and provided with 10 binding elements constituting chin straps or the like.

Another object of the invention is to provide a portion of the same general nature as the earlap portion and designed to protect 15 the face of wearer, and which will be termed hereafter a "face portion".

One of the principal objects is to provide a structure whereby chin straps are produced as integral portions of an earlap portion in 20 a manner necessitating a minimum amount of material, entailing absolutely no waste, and requiring the least amount of time expenditure, and skill.

A feature of the invention lies in manufacturing the cap in accordance with a 25 method whereby a single series of operations will simultaneously produce the earlap portion, the chin straps, and the face portion. More particularly, it is a feature of the 30 invention to include in the method of manufacture a series of extremely simple operations in the nature of slitting a blank of material in a manner whereby all the portions referred to will be simultaneously 35 produced.

Another object of the invention is to provide a cap particularly suitable for infants 40 and constructed of a single tubular blank of preferably knitted material, the various portions of the completed article forming integral portions of the original blank and being so constructed and arranged as to present a neat and compact appearance and to produce a finished article of high quality and efficiency.

A feature of the invention lies in constructing the entire completed article from a 45 single tubular blank having a length no greater than the peripheral distance from the tip of the crown to the lower edge of the earlap portion; and in utilizing a right cylindrical blank, or one which can be initially formed from a rectangular piece of material, whereby absolutely no waste of material is entailed, and whereby quantity 50 production will permit more caps per unit.

inal material to be produced than has been possible heretofore.

In a preferred method of manufacture, the slitting operation consists in making only two symmetrical U-shaped cuts into the 60 lower edge of the blank in a manner which will be described more fully hereinafter. More particularly, these slits are disconnected from each other in a particular manner so that an earlap portion is produced 65 having forwardly projecting chin strap extensions, and a face portion is produced comprising a nose-guard and lateral extensions adapted to nest normally with said extensions.

For the attainment of the foregoing objects and such other objects as may hereinafter appear or be pointed out, I have illustrated one embodiment of my invention in the accompanying drawings, in which

Fig. 1 is a perspective view of the original tubular blank, showing the disposition of the slits, and showing in dotted lines the method of constructing the crown portion;

Fig. 2 is a front perspective view of the 80 finished article in normal position;

Fig. 3 is a similar view, showing the cap applied to the head of a wearer, with the earlap portion in use; and

Fig. 4 is a similar view of the cap upon 85 the head of a wearer showing both the earlap portion and the face portion in operative positions.

Referring to the drawings, and particularly to Fig. 1, it will be seen that I have 90 taken a right cylindrical tubular blank 10 and have secured together the upper edge of the blank to form a head portion 11 substantially hemispherical in shape and provided at the tip of the crown with a tuft or 95 pompon 12 of any suitable sort. The marginal lower portion of the tubular blank 10 will constitute, when the article is completed, an integral portion capable of being doubled back over the head portion 11 100 along a transverse fold 13 to form a hinged portion comprising an earlap portion and a face portion.

In accordance with my method of manufacture, I make two symmetrical slits into the 105 lower edge 14 of the blank 10, the slits being cut substantially along lines denoted by the reference numerals 14¹ and 15, that is, along lines defining symmetrically disposed disconnected U's each of which has substan-

tially parallel arms extending diagonally upward toward the front of the cap. The material bounded by each U-shaped slit will constitute an integral chin strap extension 5 16 forwardly projecting from, and narrower than, the rear and side portions of the integral hinged portion which has been made to constitute an earlap portion. The material between the slits constitutes the face portion 10 17 and comprises a nose-guard portion 18 and lateral extensions 19, the edges of the nose-guard portion and the inner edges 20 of the extensions defining in effect cut-out portions for the eyes of the wearer when 15 the face portion is in use. This feature is clearly shown in Fig. 4. It will be obvious that the extensions 16 will normally nest with the face portion 17 by completely occupying the cut-out portions just referred to. 20 Means are provided for detachably attaching the extensions 16 and the face portion 17 to the crown portion 11 when the cap is in normal position. I have illustratively shown buttons 21 carried by the crown portion 25 11 and adapted to engage with button holes adjacent to the tips of the extensions 16; and I have shown buttons 22 similarly carried by the crown portion 11 and adapted to be engaged by button holes provided at 30 the extremities of the extensions 19.

For the purpose of enabling the chin strap extensions 16 to be attached together when they are brought beneath the chin of a wearer, I provide one thereof with a button 35 23 adjacent to the button hole and adapted to engage the button hole in the other chin strap. It will be noted that the button 23 is normally invisible, being attached to the underside of the chin strap when the latter 40 is in normal position attached to the crown 11.

I also prefer to provide buttons 24 at or near the junction of the chin straps 16 with the earlap portion, these buttons being also 45 normally invisible, and being so disposed as to be engageable by the button holes in the extensions 19 when the face portion is brought downwardly into use.

It will be noted that where knitted material is employed I have utilized the normal elasticity thereof because although the chin straps 16 normally nest with the face portion 50 17 when the cap is in normal position, nevertheless they are drawn out of this nested position when the earlap portion is lowered. As a result the cut-out portions 55 into which the chin straps normally nest are made available for registering with the eyes of the wearer. I consider this an important 60 feature of the invention because I am enabled to produce a cap which is extremely simple in construction and method of manufacture, requiring even less material than has been necessitated heretofore, and nevertheless 65 provided with protecting portions

which cooperate in a very efficient manner in protecting not only the ears but also the major portion of the face of the wearer. In view of this feature, it will be obvious that my cap is not limited to infants' use 70 nor to knitted material, and may find extensive use in a vast number of other applications.

It will also be obvious that I have constructed the cap in such a manner that if 75 desired, the earlap portions alone may be utilized. The face portion 17 in such an event constitutes a rather pleasing ornamentation for the front of the cap. It is easily conceivable that for certain uses the 80 face portion may not be desirable at all, and in such a case I may construct the cap to have the face portion permanently attached by any suitable means to the crown portion 11. It will thus be seen that my invention 85 has produced a highly efficient article, the possibilities of its uses and application being merely illustrated and suggested in the present specification. It will be noted further that its method of manufacture is of 90 extreme simplicity and cheapness, and although I have shown one form of carrying out my method, various modifications thereof may be made by those skilled in the art 95 without departing from the spirit of the 95 invention.

It is therefore intended that the various details herein described and illustrated for the purpose of explaining the nature of my invention be interpreted as illustrative, and not in a limiting sense.

Having thus described my invention and illustrated its use, what I desire to secure by Letters Patent is:

1. A cap comprising an upper head portion, and a lower portion integral therewith, said lower portion being capable of being folded back onto the head portion along a transverse fold, said lower portion having flaps at the front thereof formed by two unconnected, symmetrically arranged slits, each slit being substantially U-shaped, the U's being upside down and having their axes angularly upward toward each other when the lower portion is turned down, one 115 of the legs of each U extending to the edge of said lower portion.

2. A cap, an ear-lap portion on said cap, a portion on said cap which is ornamental when turned up and capable of functioning 120 as a face guard when turned down, said cap comprising an upper head portion, and a lower portion integral therewith, said lower portion being capable of being folded back on to the head portion along a transverse 125 fold, said lower portion having flaps at the front thereof formed by two unconnected and independent slits symmetrically arranged at each side of a vertical line drawn through the front thereof, each slit being 130

- slanting U-shaped, the axes of the two U's being angularly upward toward each other when the lower portion is turned down, the slits being nearest each other at the curved 5 base parts of the U's, the lower leg of each U when the lower portion is turned down extending to the lower edge of said flap, said lower portion providing said ear-lap portion, the portion between the U's providing said 10 portion which is ornamental when turned up and capable of functioning as a face-guard when turned down, and means to removably fasten each side of said last mentioned portion to prevent flapping thereof.
- 15 3. A cap comprising an upper head portion, and a lower head portion integral therewith, the lower portion comprising an earlap portion, two chin strap portions, and an ornamental portion shaped so as to normally 20 nest between said chin strap portions, fastening means to fasten said nesting portions in normal nesting positions when turned up, fastening means to fasten said ornamental portion when turned down so as 25 to provide a face guard thereof, and fastening means to fasten said chin strap portions together when turned down.
4. A cap comprising an upper head portion, and a lower portion integral therewith, 30 said lower portion being capable of being folded back onto the head portion along a transverse fold, said lower portion comprising an earlap portion and at the front there-
- of three internesting portions, two of said internesting portions being symmetrical chin straps, and the third internesting portion being shaped to nest between and about the chin straps and being ornamental when turned up and capable of functioning as a 35 face guard when turned down.
5. A cap comprising an upper head portion, and a lower portion integral therewith, said lower portion being capable of being folded back onto the head portion along a 40 transverse fold, said lower portion having flaps at the front thereof formed by two unconnected and independent curved slits, whereby the said lower portion of the cap is divided into three parts, each of which 45 parts is adapted to be turned up or down independently of the other parts.
6. A cap comprising an upper head portion, and a lower portion integral therewith, said lower portion being capable of being 50 folded back onto the head portion along a transverse fold, said lower portion having flaps at the front thereof formed by two unconnected and independent slits, each slit comprising a curve substantially doubled 55 back on itself, whereby the said lower portion of the cap is divided into three parts, each of which parts may be turned up or down independently of the others.

In witness whereof, I have signed this specification this 14th day of October, 1925.

MORRIS BLOOMFIELD.
